UNITED STATES PATENT OFFICE.

GEORGE KUNDEL, OF NEW YORK, N. Y.

DESIGN FOR COMBINED LAMP SHADE AND STAND OR AN ARTICLE OF SIMILAR NATURE.

Application filed April 15, 1924. Serial No. 9,290. Term of patent 3½ years.

To all whom it may concern:

Be it known that I, GEORGE KUNDEL, a citizen of Austria, having declared my intention of becoming a citizen of the United States, residing at New York city, in the county and State of New York, have invented a new, original, and ornamental Design for a Combined Lamp Shade and Stand or an Article of Similar Nature, of which the following is a specification, reference being had to the accompanying drawing, forming a part thereof.

The figure is a perspective view of a combined lamp shade and stand showing my new design.

I claim:

The ornamental design for a combined lamp shade and stand, or an article of similar nature, as shown.

In testimony whereof I affix my signature.

GEORGE KUNDEL.
